UNITED STATES PATENT OFFICE.

FELDER A. BURNAM, OF MEDINA, NEW YORK.

UMBRELLA.

SPECIFICATION forming part of Letters Patent No. 484,773, dated October 25, 1892.

Application filed September 19, 1891. Serial No. 406,166. (No model.)

To all whom it may concern:

Be it known that I, FELDER A. BURNAM, of Medina, in the county of Orleans, in the State of New York, have invented new and useful

5 Improvements in Umbrellas, of which the following, taken in connection with the accompanying drawings, is a full, clear, and exact description.

10 My invention relates to improvements in umbrellas, and has for its object the production of a simple and effective device, which is cheaply produced and greatly lengthens the life and appearance of the umbrella by permitting the extremity of the umbrella-15 stick to be replaced when broken, injured, or worn.

20 To this end it consists, essentially, in a cover having an opening through which the end of the stick passes, a notch mounted on the stick, 25 having ribs hinged thereto, and an umbrella-stick consisting of a lower section, having an annular shoulder for supporting the notch and a projecting spindle above said shoulder, and an upper section adapted to be passed through the opening in the cover and provided with a socket for detachably engaging the spindle on the lower section and with a shoulder for supporting the cover, and in the detail construction and arrangement of the 30 parts, all as hereinafter more particularly described, and pointed out in the claims.

35 In describing this invention reference is had to the accompanying drawings, forming a part of this specification, in which like letters indicate corresponding parts in all the views.

40 Figure 1 is an enlarged elevation, partly in section, of the upper extremity of the umbrella-stick and the cover, illustrating the relative construction and arrangement of the parts. Fig. 2 is an elevation of the detached upper extremity of the cover. Fig. 3 is a vertical sectional view of the cover as shown at Fig. 3, and Fig. 4 is an enlarged top 45 plan view of the lower section of the umbrella-stick and the cover mounted thereon.

45 It is well known that considerable difficulty is at present experienced in providing an umbrella with a new stick and that frequently 50 the extremity of a stick becomes broken and necessitates an entire new stick.

My invention is designed to permit either the repair of the stick or the substitution of a new stick with a minimum degree of expense, inconvenience, and time.

55

The umbrella-cover A is suitably secured to the supporting-ribs B, and is provided with a central aperture a, having a metallic ring or sleeve a', and cords a² for suitably securing said cover to the ribs B. The metallic ring a' consists of an upper plate a³, having a depending flange a⁴ and a lower plate a⁵, upon which the lower face of said depending flange a⁴ is turned or spun for securing the two plates together, and interposed between said 60 upper and lower plates a³ a⁵ and the cover are suitable washers a⁶, formed of leather, cloth, or other suitable material. It will be noted that a ring a', formed of two separate plates, as described, is more readily attached 70 than when formed of a single piece having two integral flanges above and below the cover, and that as the depending flange a⁴ is turned or spun outwardly for securing said plates together the lower plate a⁵ forms a firm 75 support for the flange.

E represents the umbrella-stick consisting of two sections e e', detachably secured together. These sections are preferably separable at the point where the notch D is supported thereby, said sections being provided with shoulders e², separated by a smooth face and formed by an annular groove e³ in the stick E for receiving the notch D, in order that its top and bottom edges may bear 80 against said shoulders, and be thereby prevented from lengthwise movement on the stick. This notch D is firmly held from revolution by a pin d, passed through the same and the stick E.

85

90 Extending upwardly from the shoulder e² of the section e', in the same plane as the top shoulder of the notch D, is a screw-threaded nipple e⁴, adapted to enter a screw-threaded socket e⁵ in the detachable section e' for 95 firmly securing together said sections e and e', as best seen at Fig. 3. The lower section e may be formed of wood or other suitable material and the upper section of metal or other material possessing greater strength than the 100 wood, in order to prevent breakage of said extremity and increase its durability.

F is an annular shoulder formed on the detachable extremity e' for engaging the sleeve or ring a' and supporting the cover.

It is apparent that should the extremity e' become worn or injured it may be readily replaced by unscrewing the same from the section e, which is then drawn away from the cover in order to permit the section e' to pass within the cover before the two sections are secured together.

When the repaired stick or a new one is to be operatively secured to the cover, the detachable extremity is passed from the inside of the cover to its normal position. The section e is then passed through the notch D and the two sections screwed together by turning the detachable extremity e'.

The operation of my invention will be readily perceived from the foregoing description and upon reference to the drawings; and it is evident that the umbrella-stick may be readily separated from the cover for repair, either of the cover or of the stick, or for the insertion of a new handle.

Having thus fully described my invention, what I claim as new, and desire to secure by Letters Patent, is—

1. As an improved article of manufacture, the herein-described umbrella, the same consisting of a cover provided with a central opening and with hinged ribs, an umbrella-stick comprising a main section e and a removable section e', passed through the opening of the cover with its outer end projecting beyond the cover and its inner end formed with a shoulder engaged with the inner face of the portion of the cover surrounding said

opening, and a notch secured to the stick-section e and adapted to support the inner ends of said ribs, substantially as described.

2. As an improved article of manufacture, the herein-described umbrella, the same comprising a cover provided with a central ring a' and with ribs B, having their outer ends secured to the cover, a main stick-section e, having a hand-engaging portion at its outer end and an annular shoulder at its inner end, said stick-section being provided at said inner end with a nipple projecting beyond said annular shoulder and formed with an annular shoulder, and with screw-threads above said shoulder and a plane face beneath the same, a notch for supporting the inner ends of said ribs rigidly secured to the spindle and interposed between said shoulders with its lower end resting upon the lower shoulder, and a detachable stick section or extremity e', passed through said ring with its outer end projecting beyond the same and provided at its inner end with a central socket for receiving the screw-threaded end of the spindle and with an enlarged shoulder F, bearing against the top face of said notch and the under face of said ring, substantially as and for the purpose specified.

In testimony whereof I have hereunto signed my name, in the presence of two attesting witnesses, at Medina, in the county of Orleans, in the State of New York, this 31st day of August, 1891,

FELDER A. BURNAM.

Witnesses:
